HIS ATTORNEYS.

UNITED STATES PATENT OFFICE.

JAMES H. RAND, OF NORTH TONAWANDA, NEW YORK.

INDEX.

1,306,026.

Specification of Letters Patent. Patented June 10, 1919.

Application filed August 23, 1918. Serial No. 251,073.

To all whom it may concern:

Be it known that I, JAMES H. RAND, a citizen of the United States of America, and resident of North Tonawanda, in the county 5 of Niagara and State of New York, have invented new and useful Improvements in Indexes, of which the following is a specification.

This invention relates to indexes of the 10 so-called overlapping card, visible index, type and consists in the novel features hereinafter described and particularly pointed out in the claims.

In the accompanying drawings which 15 illustrate certain embodiments of the invention,--

Figure 1 is a front view of the index, parts being broken away, illustrating the preferred form of the invention;

20 Fig. 2 is a longitudinal central section through Fig. 1;

Fig. 3 is a cross section of the index frame shown in Figs. 1 and 2; and

25 Fig. 4 illustrates a modification in the construction of the frame.

The index frame, which is preferably made of sheet metal, comprises the back 1, the side margins of which are bent over to form inwardly extending flanges 2 forming 30 opposed channels disposed lengthwise of the frame. Guide flanges 3 for the purpose hereinafter explained project forwardly from the front face of the channel flanges. These guide flanges are preferably each 35 formed of an angle strip of which one leg is secured to the frame, while the other leg projects from the face of the channel flange at the outer edge of the frame and of the channel flange thus forming a guide flange 40 at each side of the frame. Each such angle strip, which may be made of sheet metal bent as shown, preferably has one leg 4 secured to the rear of the frame, with the other leg 3 constituting the guide flange extending 45 across the side edge of the frame and forwardly beyond the face of the channel flange. The leg 4 of the strip is preferably made wider than the channel flange 2 so that it may be secured to the back of the frame at 50 places not overlapped by the channel flange. This is desirable for the reason that the channel under flange 2 is so narrow that it would be difficult to apply fastening means within the channel. The member 4 may be 55 secured to the back 1 of the frame by rivets, soldering, welding or other means, all of

which can be applied more conveniently and effectively at an area not overlapped by the flange 2.

The index elements supported by the 60 frame consist of cards C having laterally projecting members a adjacent to one margin and extending under and engaged by the channel flanges 2. The cards C are also provided with laterally projecting members 65 b on the free portion of the cards overlying the outer face of the channel flanges 2 at the inner sides of the guide flanges 3. The cards are mounted in the frame in overlapped spaced relation, as by providing each card 70 with a tongue d formed from the body of the card and bent rearwardly sufficiently to engage and support the lower edge of the next adjacent card. Other means of mounting the cards in overlapped spaced relation with 75 their free margins exposed for the purpose of receiving index characters may be used, and it will also be understood that the projections a and b, while shown as integral parts of the cards C, might if desired be 80 formed of separate pieces attached to the cards. The projections b resting on the front faces of the flanges 2 hold the cards at a slight inclination forward so that they may be readily grasped and bent forward 85 for inspection or the making of entries, and also hold the cards in convenient position for the insertion of additional cards at any point in the series. It will be understood that the cards may be slid lengthwise of the 90 frame for the purpose of inspecting, assembling or removing them. The term "cards" is used both in the specification and claims to denote not only sheets of cardboard, but any similar index element made of any suitable sheet material. 95

Any tendency of the cards to become displaced laterally from their proper position in the frame, either accidentally or incidentally to the manipulation, will be obviated 100 by the guide flanges 3, which engage the extremities of the projection b and hold the cards straight in the frame.

In the modification shown in Fig. 4 the angle strip which forms the guide flange has 105 one leg 4^a secured to the channel flange 2, instead of the back 1 of the frame as in the other form, while the guide flange 3^a corresponds in position and function to guide flange 3 of the other form. 110

I claim:

1. An index comprising a frame having

- inwardly extending flanges forming opposed channels disposed lengthwise of the frame and guide flanges projecting forwardly from the face of the channel flanges, and a series 5 of cards mounted in the frame in overlapped spaced relation having laterally projecting members extending under and engaged by said channel flanges, and laterally projecting members on the free portion of the cards 10 overlying the outer face of said channel flanges at the inner sides of the guide flanges, whereby the cards will be guided by the guide flanges against lateral displacement.
- 15 2. An index comprising a frame having inwardly extending flanges forming opposed channels disposed lengthwise of the frame and guide flanges at the outer edges of the frame projecting forwardly from the face 20 of the channel flanges, and a series of cards mounted in the frame in overlapped spaced relation having laterally projecting members extending under and engaged by said channel flanges, and laterally projecting 25 members on the free portion of the cards overlying the outer face of said channel flanges at the inner sides of the guide flanges, whereby the cards will be guided by the guide flanges against lateral displacement.
- 30 3. An index comprising a frame having inwardly extending flanges forming opposed channels disposed lengthwise of the frame and guide flanges at the outer edges of the channel flanges projecting forwardly from 35 the face of the channel flanges, and a series of cards mounted in the frame in overlapped spaced relation having laterally projecting members extending under and engaged by said channel flanges, and laterally projecting 40 members on the free portion of the cards overlying the outer face of said channel flanges at the inner sides of the guide flanges, whereby the cards will be guided by the guide flanges against lateral displacement.
- 45 4. An index frame having inwardly extending flanges forming opposed channels disposed lengthwise of the frame, and guide flanges projecting forwardly from the face 50 of the channel flanges.
5. An index frame having inwardly extending flanges forming opposed channels disposed lengthwise of the frame, and guide flanges at the outer edges of the frame projecting forwardly from the face of the channel flanges. 55
6. An index frame having inwardly extending flanges forming opposed channels disposed lengthwise of the frame, and guide flanges at the outer edges of the channel flanges projecting forwardly from the face 60 of the channel flanges.
7. An index frame having inwardly extending flanges forming opposed channels disposed lengthwise of the frame, and strips 65 secured thereto, forming guide flanges projecting forwardly from the face of the channel flanges.
8. An index frame having inwardly extending flanges forming opposed channels 70 disposed lengthwise of the frame, and a pair of angle strips, one leg of each of which is secured to the frame and the other leg of which projects forwardly beyond the face of one of the channel flanges and constitutes 75 a guide flange.
9. An index frame having inwardly extending flanges forming opposed channels disposed lengthwise of the frame, and a pair 80 of angle strips, one leg of each of which is secured to the rear of the frame and the other leg of which extends across the side edge of the frame and forwardly beyond the face of the channel flange to form a guide flange. 85
10. An index frame having inwardly extending flanges forming opposed channels disposed lengthwise of the frame, and a pair 90 of angle strips, one leg of each of which is wider than the channel flange whereby it may be secured to the back of the frame at places not overlapped by the channel flanges and the other leg of which extends across the side edge of the frame and forwardly beyond the face of the channel 95 flange to form a guide flange.

Signed by me at North Tonawanda, N. Y., this 16th day of August, 1918.

JAMES H. RAND.
